INSULATED REFRIGERATOR CASING

Harvey B. Lindsay, Chicago, Ill., assignor to Dry-Zero Corporation, Chicago, Ill., a corporation of Delaware

Application March 12, 1936, Serial No. 68,367

3 Claims. (Cl. 220—14)

The object of this invention is to automatically dispose, without dripping, of the moisture that usually gathers on the bottom of the insulation space of a refrigerator more particularly if it is insulated with substantially non-hygroscopic or non-absorptive insulating material.

It has been proven that humidity in the air functions as a true gas; that it is not minute droplets of water carried directionally by the air. 10 It is also known that this gas of H_2O is nearly twice as tenuous as the air mixture and under the laws of gases nearly four times as penetrative.

As it is impossible commercially to build the 15 walls of a refrigerator, etc., so gas-tight that they would maintain a vacuum successfully, it is obvious that it is impossible to keep out this gas of H_2O —commonly called water vapor—which is nearly four times as penetrative as air.

It is a fact, and the above explains it, that 20 water gradually but inevitably forms in the insulation space of a refrigerator or refrigerator chamber under refrigeration. This water comes from the penetration of water vapor through the porosities or cracks of the outside shell, this water vapor being under definite vapor pressure to penetrate to the cold side.

At first this water vapor that is penetrating 25 the outside shell, condenses on the outside surface of the inside liner of the refrigerator and in intimate contact with the usual so-called "waterproof" wrapping supposed to protect the insulation. As this wrapping becomes cold from its moist contact with the cold liner, however, the 30 condensation then begins to take place on the face of the wrapping next the insulating material and in intimate contact with the latter. Thereupon two forces are set up on this water of condensation: The forces of absorption, mostly 35 capillarity of the insulating material, and the surface repulsion of that material for water (as for example, that of wax).

If the surface repulsion exceeds the capillary forces, the insulating material will remain dry 40 indefinitely. But if the capillary forces exceed the surface repulsion of the material it will gradually become damp, moist or wet. In the first instance the insulation is referred to as "non-hygroscopic", in the second, "hygroscopic".

In the case of a refrigerator insulated with 45 non-hygroscopic insulation, while the condensation described above will form on the outer surface of the liner, it will trickle down and eventually form a pool of water at the bottom of the refrigerator. If the wrapper becomes wet and 50

cold and condensation then occurs between it and the non-hygroscopic insulant, the latter refuses to get moist and such condensation finds its way down the wrapper and out of the joints of same at the bottom of the slab or package of such insulant, and so into the bottom of the refrigerator shell. Where lined with hygroscopic insulating material, the condensation is absorbed in the insulation to eventual saturation. 5

This explains why refrigerators insulated with 10 non-hygroscopic material and in use for some time will often show water dripping or running down the legs. If the bottom of the refrigerator is a water-tight pan fastened to the sides and back, then if the refrigerator is tilted the water 15 runs out in considerable quantities. As stated, this invention is for the purpose of disposing of the water so forming in the bottom of a refrigerator, or substantially such, without any sign of drip or running down the legs. 20

I am aware that certain devices have been proposed in the nature of air valves designed in the hope that they would effect the expulsion of water vapor by "breathing", but such efforts have proved impractical for this purpose. The device 25 of the present invention, however, operates upon an entirely different principle, as will presently appear. 20

The invention may best be understood by reference to the accompanying drawing, in which 30

Fig. 1 is a vertical section of a refrigerator chamber and its insulating space through a median plane between front and back, and including a moisture-disposal device constructed in accordance with my invention. 35

Fig. 2 is a horizontal detail section taken on line 2—2 of Fig. 1. 40

Fig. 3 is a fragmentary vertical section showing a modified form of moisture-disposal device constructed in accordance with my invention. 45

Fig. 4 is a detail section showing a still further modification of the form of device shown in Fig. 3. 50

Referring now to details of the embodiment of my invention illustrated in Figs. 1 and 2, the refrigerator casing is indicated generally at 10, and 45 includes an outside shell 11, such as sheet steel or the like, an inner or inside lining 13, usually of porcelain enameled steel, and insulating material 12 of any suitable form between the outside shell 11 and inner liner 13. The insulating material 12 is preferably non-hygroscopic, although the inner wrapper or layer only of the insulating material adjacent the inner lining 13 may be non-hygroscopic, if desired. As shown in Fig. 1, the four upper edges of the bottom slab of insu- 55

lating material may be beveled as at 12^a, to assist in directing water of condensation downwardly along the side slabs of insulation.

The bottom 11^a of the shell 11 is provided with 5 a small discharge passage or hole 14, preferably at or near its center, and preferably having a plurality of drainage channels 15 depressed in said bottom, said channels being arranged radially of and tapering downwardly toward said hole, 10 as shown in Figs. 1 and 2.

On the exterior of the bottom 11^a and below the discharge hole 14, is mounted a sheet 16 of self-supporting absorptive material, such as the board forms of insulation known in the industry 15 as "Celotex", "Insulite" or the like. The sheet 16 is suitably supported against the bottom 11^a as by cleats or channels 17 welded or soldered to said bottom wall.

In the modified form of the invention illustrated in Fig. 3, a separate pan 18 is supported above the bottom slab 12 of insulation, said pan being slightly dished toward a center aperture 19. The edges of said pan extend slightly beyond the lateral sides of liner 13 so that water trickling 25 down the sides of said liner will be caught by said pan. A suitable hole or channel 20 is formed in the bottom slab of insulation 12^b beneath the aperture 19 and affording communication to the discharge passage 14^a in the bottom 11^a of the shell 11. An absorptive board 16 is secured beneath the passage 14^a as in the form of device 30 shown in Fig. 1.

In the form shown in Fig. 4, the arrangement is similar to that illustrated in Fig. 3, excepting 35 that a tube 21 extends through hole 20 and connects the aperture 19 of pan 18 with the discharge passage 14^a, as shown. This arrangement is preferable where the bottom slab of insulation is partially or wholly hygroscopic.

40 In operation, moisture condensing on the top, sides and back of the liner and being refused by the adjacent non-hygroscopic insulation will trickle down the liner and either seep between the side insulation and the bottom insulation to the 45 bottom of the shell and there trickle to the hole in the middle of the latter; or, with the pan as in Figs. 3 and 4, the moisture trickling down the liner will be caught in the pan, led to the hole 20 and thence to the discharge hole 14^a in the 50 bottom of the shell.

On reaching this hole in the bottom of the shell, the water will be absorbed by the sheet of absorptive material 16, spreading laterally through said sheet considerably, and gradually 55 towards the bottom surface, and on reaching that bottom surface will evaporate to the surrounding air. Thus the hole 14 is effectively sealed against passage of heat or ordinary air currents into the insulation space, and yet the water of condensation 60 may escape through the sheet of absorptive material by dispersion and evaporation. Further, the minute channels through the material of the evaporator "board" being substantially filled with the water seeping from the escape hole to the

evaporating surface, ingress of water vapor therethrough is reduced to a negligible amount.

Experiment has shown that this is a constant operation. The evaporating sheet 16 can of course be covered with perforated metal or with wire gauze, if desired, without interfering with its evaporating functions.

While the hole 14 can be quite small and yet take care of all the moisture as it forms and reaches the hole, the evaporating surface of evaporator board 16 must be sufficient to dispose by evaporation of all moisture reaching and soaking into the evaporator board. Experiment has shown that even under the severest conditions obtaining in a kitchen and with a very faulty 15 outside shell to the refrigerator (full of openings and seams) an evaporating area of 30 square inches is quite sufficient. Of course, the better the shell (the more it retards water vapor entry) and the better the conditions (the less humidity 20 in the air) the less area of evaporating board is required under those conditions.

In those forms of refrigerating devices, for example an electric domestic refrigerator, where the machine is below the insulated food chamber 25 the warm air from the condenser not only accelerates the desired evaporation from the evaporator "board", but the evaporation tends to cool the ambient air and so increase the efficiency of the condenser. However, all that is required for 30 the satisfactory operation of this invention is reasonably free access of air to the evaporator "board".

Although I have illustrated and described certain embodiments of my invention, it will be understood that I do not wish to be limited to the exact construction shown and described, but that various changes and modifications may be made without departing from the spirit and scope of my invention as defined in the appended claims. 40

1. In a refrigerating device, an outer casing and an inner lining having insulation material therebetween, said outer casing having a water discharge opening at the bottom thereof, and a sheet of absorptive material secured to said outer casing and covering said discharge opening. 45

2. In a refrigerating device, an outer casing and an inner lining having insulation material therebetween, said outer casing having a water discharge opening at the bottom thereof, and a sheet of absorptive material secured to said outer casing and covering said discharge opening, but having its exterior surface evaporatively exposed to the surrounding air. 50

3. In a refrigerating device, an outer casing 55 and an inner lining having insulation material therebetween, said outer casing having a water discharge opening at the bottom thereof, means below said inner lining for directing water of condensation from the sides of said lining to said 60 discharge opening, and a sheet of absorptive material secured to the bottom of said casing and closing said discharge opening to the outer air.

HARVEY B. LINDSAY.
